UNITED STATES PATENT OFFICE.

JOHN G. RIDINGS, OF AMARILLO, TEXAS, ASSIGNOR OF TWO-THIRDS TO
CLAUDE D. JACKSON, OF SAME PLACE, AND AUGUST BUERMANN, OF
NEWARK, NEW JERSEY.

DESIGN FOR A BRIDLE-BIT.

SPECIFICATION forming part of Design No. 34,969, dated August 20, 1901.

Application filed April 16, 1901. Serial No. 56,015. Term of patent 7 years.

To all whom it may concern:

Be it known that I, JOHN G. RIDINGS, a citizen of the United States, residing at Amarillo, in the county of Potter and State of Texas, 5 have invented and produced a new and original Design for a Bridle-Bit; and I do hereby declare the following to be a full, clear, and exact description of the invention, such as will enable others skilled in the art to which 10 it appertains to make and use the same, reference being had to the accompanying drawings, and to letters of reference marked thereon, which form a part of this specification.

Figure 1 is a perspective view, and Fig. 2 is 15 a side elevation, of my newly-designed bridle-bit.

The leading or material feature of my design, as shown in the drawings, consists in the horse-shaped cheek parts of the bit with the 20 specific configurations hereinafter specified.

In said drawings, *a* indicates the mouth part, and *b* the cheek parts, of the bit, in the latter of which the novelty of design more particularly inheres.

c is the horse-shaped body of the cheek-piece, which in side elevation presents to view a single fore leg doubled so that the heel of the hoof lies close to the upper part of the leg, the hind legs being spread apart so that the hoofs thereof lie distant one from the 30 other, the lower parts of said hind legs lying concentric with a semicircular configuration *d*, connecting said hind legs. At the opposite ends of the horse-shaped body part from the said semicircular connecting part *d* the 35 forehead of the horse-shaped part lies upon or at a ring-shaped part *e*.

What I claim as new is—

The design for a bridle-bit, substantially as 40 shown and described.

In testimony that I claim the foregoing I have hereunto set my hand this 29th day of March, 1901.

JOHN G. RIDINGS.
